[57] CLAIM

The ornamental design of a transporting device for bath- and toilet purposes, as shown and described.

DESCRIPTION

FIG. 1 is a front elevation of a transporting device for bath and toilet purposes showing my new design;

FIG. 2 is a perspective view thereof;

FIG. 3 is a top plan view thereof;

FIG. 4 is a right side elevation thereof;

FIG. 5 is a left side elevation thereof;

FIG. 6 is a perspective view of a modified embodiment of the transporting device illustrated in FIG. 2;

FIG. 7 is a top perspective view of the bath seat shown in FIG. 6, the seat is disclosed separately for clarity of illustration;

FIG. 8 is a top plan view thereof with the retainer belt omitted therefrom; and

FIG. 9 is a side elevation.

FIG. 3.

FIG. 1.

Fig. 7.

Fig. 8.

Fig. 9.
